UNITED STATES PATENT OFFICE

160,494

NUTCRACKER

Arnold B. Hagen, Seattle, Wash.

Application April 17, 1948, Serial No. 145,784

Term of patent 3½ years

(Cl. D44—1)

To all whom it may concern:

Be it known that I, Arnold B. Hagen, a citizen of the United States, residing at Seattle, in the county of King and State of Washington, have invented a new, original, and ornamental Design for a Nutcracker, of which the following is a specification, reference being had to the accompanying drawings, forming part thereof.

In the drawings—

Fig. 2 is a front elevational view of the same.

I claim:

The ornamental design for a nutcracker, as shown.

ARNOLD B. HAGEN.
